UNITED STATES PATENT OFFICE.

EDGAR H. CLARK, OF RICHMOND HILL, NEW YORK, ASSIGNOR TO WESTERN ELECTRIC COMPANY, INCORPORATED, OF NEW YORK, N. Y., A CORPORATION OF NEW YORK.

NUMBER-INDICATING SYSTEM.

Application filed December 26, 1919. Serial No. 347,510.

To all whom it may concern:

Be it known that I, EDGAR H. CLARK, a citizen of the United States, residing at Richmond Hill, in the county of Queens, State of New York, have invented certain new and useful Improvements in Number-Indicating Systems, of which the following is a full, clear, concise, and exact description.

This invention relates to number indicating systems and more particularly to number indicating systems adapted for use in automatic telephone exchange systems.

It is the object of this invention to provide means such that the position assumed by a selective device of any type may control a number indicating device to register a numeral corresponding to the particular position which such device has assumed.

It is a further object of this invention to provide means such that in case a number of switching devices have access to a group of lines which are consecutively numbered, and in case such group of lines is divided into a number of subgroups each consecutively numbered within certain numerical limits, a number indication may be produced which will indicate which line of the main group has been seized, this number indication being determined in accordance with which switch was operated and in accordance with the position assumed by such switch.

A feature of the invention is an arrangement such that the position taken by the selecting device sets up certain conditions by means of certain contacts controlled by it so that the proper number indication may be controlled in accordance with such setting.

It is an additional feature of the invention to provide means, individual to each group of lines served by a switching device, to position corresponding controlling devices so that the display of the number will not only convey information in regard to the number of the line in the selected group, but will also convey the complete number as determined by the group and the particular line in the group selected. It is obvious that if each switching device had access to merely ten lines, this designation would be readily accomplished, but when a switching device serves lines which are greater or less in number than ten, the required transla-

tion introduces difficulties which it is the purpose of this invention to overcome.

The invention has been applied to, and the circuits as shown are arranged to cooperate with, the system shown in application Serial No. 301,891, filed June 5, 1919 by A. E. Lundell and E. H. Clark. The scope of the invention, however, obviously includes a variety of uses and is therefore to be limited only by the appended claims.

It is thought that the invention will best be understood from the following detailed description, reference being had to the accompanying drawings. In the drawings Fig. 1 shows the substation equipment of a calling subscriber, an "A" operator's manual cord circuit and portions of a trunk circuit leading to an automatic office, as well as a set of relays, there being one relay individual to each group of trunks leading to mechanical offices similar to the office indicated at 123, 124 and 125. Fig. 2, which is to be placed to the right of Fig. 1 shows circuit controlling equipment common to the various operators in the exchange. In the lower left-hand portion of this figure is indicated an operator's finder switch of the type disclosed in the above-mentioned application. To the right of the vertical dotted line are shown the circuits of a finder and impulse sending switch which operates in conjunction with the trunk selector switch whose circuits occupy the remainder of the drawing. Fig. 3, which is to be placed below Fig. 1, shows the operator's controlling key set and a portion of the controlling relays for the number indicating device. Fig. 4, which is to be placed to the right of Fig. 3, shows the number indicating lamps and certain other controlling relays therefor.

Since the invention is concerned only with the number indicating feature, the complete operation of the system will not be described. It is to be understood that apparatus and circuits not shown are identical with those shown in the above-mentioned application and it is to be understood that any conductors, the terminations of which are not shown in the present application lead to apparatus identical with that shown in the above-mentioned application. A like system of numbering has been employed so far as possible in order that the relation

of the present system to that shown in the above-mentioned application may be more readily understood.

In accordance with the general organization of the system in connection with which this invention has been shown, trunks terminating at the manual exchange are divided into groups, each group of trunks leading to a particular mechanical exchange and there connecting with selectively operable switching devices, to be termed incoming selector switches. Each operator at the manual exchange is provided with a set of keys on which the wanted number may be registered, and an indicator for the display of the designation of the mechanical exchange and the trunk chosen for the extension of a call.

There is provided, for the common use of all operators a group of connecting units for each of the groups of trunks leading to a mechanical exchange and a group of registering and controlling equipments accessible to all operators through the medium of any one of said connecting units. Each connecting unit consists of three automatic switching mechanisms. One of these mechanisms will be termed an "operator's finder switch" and is provided for the purpose of associating the key-set and indicating equipment of any operator with the connecting unit. A second mechanism that will be termed a "trunk selector" is provided for the purpose of associating the connecting unit with an idle trunk of the group leading to the desired mechanical exchange, and a third mechanism (not shown) that will be termed a "sender selector" is for the purpose of associating an idle registering and controlling equipment or sender with the connecting unit. All of the senders are accessible to any one of said connecting units.

An allotting and controlling mechanism (not shown) is provided for each group of connecting units. This mechanism consists of an exchange key for each mechanical exchange at each operator's position, and an allotter switch controlled by any one of the associated exchange keys to allot an idle connecting unit for the use of the operator desiring a connection to the corresponding mechanical exchange.

The manual operator, in extending a call to a subscriber in a mechanical exchange makes use of the ordinary manual cord circuit in combination with one of these connecting units. The operator ascertains the wanted number from the calling subscriber and then associates the keys and the trunk indicator with an idle connecting unit having access to a group of trunks leading to the desired exchange. The connecting unit is also automatically connected to an idle sender. The finding of an idle trunk leading to the wanted exchange and the indicating of the number of the chosen trunk

on the trunk indicator is automatically performed. The operator then proceeds, after having received a dialing tone indicating that an idle sender has been associated with the keys, to manipulate the keys and adjust the sender in accordance with the number wanted. In response to the operation of the digit keys the usual selector switches at the mechanical exchange begin to operate and associate the selected trunk with the wanted subscriber's line. During the operation of the selector switches at the mechanical office, the operator connects the outgoing end of the cord circuit associated with the calling subscriber's line, with the selected trunk, and when the selective operations at the mechanical exchange are completed, the wanted subscriber is signaled in the usual manner and the connecting unit is released and made accessible for a second call.

The selector switches at the mechanical exchange and their operating circuits are power driven switches of the well-known type and need not be described.

The various switches shown in the drawing are of the well-known step-by-step type in which a stepping pawl operates a ratchet wheel to which are connected brushes or wipers adapted to travel over the contacts of an arcuate terminal bank. These brushes or wipers are so arranged that for each step of the operating magnet the brushes or wipers engage a corresponding set of terminals. The operator's finder switch 300 is equipped with eight brushes and corresponding terminal banks, while the selector switch 400 is equipped with six brushes and corresponding terminal banks and the impulse switch 600 is equipped with five brushes and corresponding terminal banks. Switches 300 and 400 have no normal positions but stop in whatever position they are placed by their respective operating magnets. Each of these switches is arranged to have twenty terminals in a bank. The switch 600 does have a normal position and need have only seven terminals in a bank. The trunk indicator consists of three series of ordinary switchboard lamps arranged to indicate the hundreds, tens and units digits. The detailed operation of the system is as follows.

When the subscriber at station 200 removes his receiver from the switchhook the line relay 202 energizes and lights the lamp 203 by means of a circuit through its armature and front contact. On receiving this signal, the operator inserts plug 295 into jack 296 closing a circuit for cut-off relay 297 to extinguish the lamp 203. The operator then manipulates listening key 209 to connect her telephone set 211 to the subscriber's line in the usual manner.

The operator, after receiving the wanted number from the subscriber at station 200, depresses the exchange key 114 bearing the

name of the desired office. The key 114 completes a circuit from battery, through the winding of relay 207, left-hand armature and back contact of relay 210, winding of relay 205, key 114 to ground. Relays 205 and 207 become energized and lock up through the left-hand inner front contact and armature of relay 205 and the left-hand armature and back contact of relay 206. Relay 207 supplies a holding ground for the trunk indicator relays for a purpose which will appear hereinafter. Relay 205 closes a circuit at its outer right-hand front contact and armature, for the exchange lamps 208 that indicate to the operator the exchange for which the call is intended. Relay 205 also completes a circuit extending from ground over conductor 238, to put into operation an allotted controlling unit. This controlling unit when once put into operation functions as described in the above mentioned application to cause trunk selector 400 to advance until its brushes come to rest on the terminals of an idle trunk leading to the desired office, and at the same time cause operator's finder switch 300 to connect the operator's key set to an idle sender which is at the same time selected by means of a sender selector (not shown). The advance of selector switch 400 is under the control of stepping magnet 416 and the advance of finder 300 is under the control of stepping magnet 308 as is fully described in the above mentioned application.

As soon as the connecting unit is operated to connect the key set 113 to an idle sender, dialing tone is conveyed to the operator over conductor 334 through the inductive windings of coil 223 and thence by way of the outer left-hand armature and contact of relay 205 to ground through a winding or the induction coil of the operator's telephone set 211. This dialing tone indicates to the operator that an idle sender has been connected to the keys 113. The setting up of the wanted number on the keys 113 may now be begun, regardless of whether or not the trunk selector has found an idle trunk. Since the present invention is not concerned with the general operation of the system it has not been considered necessary to describe the manner in which keys 113 operate to control registration in the sender. As soon as trunk selector 400 has found an idle trunk, relay 505 is energized and completes the fundamental circuit 447 and 448 through its left-hand armatures and front contacts by connecting it to the outgoing trunk leads 507 and 508. Relay 505 completes a circuit from grounded battery, outer right-hand armature and contact of relay 505, winding of relay 509 to ground, thus causing the energization of relay 509.

Relay 509 is individual to the group of trunks leading to the desired office. Since

trunk selector 400 has access to twenty terminals, the relay 509 must control the designation of the particular group of 20 in which the trunk selected occurs. The trunk indicator is shown as arranged to have a capacity 70 to provide indications for an operator's position equipped with 160 trunks. If, then, there are twenty trunks leading to each mechanical office, there will be eight sets of switches corresponding to trunk selector 400, 75 and there will be a relay corresponding to 509, these relays being indicated in Fig. 1 by the designations 510 to 516 inclusive, individual to each such group of trunks. It is therefore obvious that if an operator de- 80 presses some other office key, some other trunk selector switch corresponding to switch 400 would have been put into operation and that some other one of the relays 510 to 516 inclusive would have been ener- 85 gized when the relay corresponding to relay 505 became energized.

Obviously the invention is not limited to this particular type of arrangement since it is readily conceivable that it would be de- 90 sirable to have more than twenty trunks running to a particular mechanical office. In this case, since each trunk selector has access to only twenty trunks, it might be necessary to provide a number of trunk selector 95 switches for each connecting unit. The operation of these switches would be such, that, provided all the trunks of the first group were busy, a circuit, which in effect would be an extended starter-wire, would cause a sec- 100 ond switch having access to twenty trunks, numbered from 20 to 39, would be started, and if all these trunks were busy a third switch, having access to trunks numbered from 40 to 59, might be started. In case of 105 an arrangement of this kind, there would have to be a relay corresponding to relay 509 individual to each group of trunks and the operation of the indicator in recording the number of the trunk selection would be the 110 same as will now be described.

It will be assumed that the switch 400, shown in Fig. 2 has access to twenty trunks and that these trunks are in the third twenty appearing at the operator's position, and are therefore numbered from 40 to 59. It will further be assumed that the trunk selected is the last trunk in the group and is therefore numbered 59.

As soon as relay 509 is energized, the operation of the indicator controlling relays and the controlling switch 600 is started. The operation of the number indicator is as follows:

Relay 509 at its right-hand armature completes a circuit from ground, contact and right-hand armature of relay 509, conductor 550, left-hand armature and back contact of relay 460, right-hand winding of relay 461, conductor 462, brush 601 in its normal po- 125

sition, conductor 602, brush 344 and its associated contact, conductor 343, inner right-hand armature and back contact of relay 250, winding of relay 251, conductor 252, 5 right-hand winding of relay 253 to battery and ground. Since ground through no resistance is supplied at the armature and contact of relay 509, marginal relay 253 is energized in this circuit, as are also sensitive relays 251 and 461. Relays 461 and 251 would have been energized even though a resistance had been included in the path to ground at the contact of relay 509. Relay 253, upon energization locks up through its left-hand 10 winding and left-hand armature and front contact to conductor 254 which is grounded at the armature and contact of relay 207 as previously described. Relay 253 at its right-hand armature and front contact completes an energizing circuit for relay 282. The left-hand armature of relay 509 completes a circuit from ground, left-hand armature and contact of relay 509, conductor 551, left-hand winding of relay 461, brush 603 in its 15 normal position, conductor 604, brush 341, conductor 340, left-hand armature and back contact of relay 250, winding of relay 255, conductor 256, right-hand winding of marginal relay 257 to battery and ground. Since 20 direct ground is supplied at the left-hand armature of relay 509, marginal relay 257 is energized. Relay 255 is also energized in this circuit. It is to be noted at this point that current flow through either of the windings of the relay 461, whether through a resistance at contacts of relay 509 or directly to ground, would have allowed sufficient current flow to energize relay 461. Marginal relay 257 locks up through its left-hand 25 winding and inner left-hand armature and front contact to grounded conductor 254. Relay 257 at its outer right-hand armature and contact completes a circuit for relay 268. Relay 268 is energized and remains energized until relay 257 deenergizes. 30

Relay 461 upon energization completes a circuit from grounded battery, winding of relay 460, left-hand armature and front contact of relay 461 to ground. Relay 460 upon energization locks up through its inner right-hand armature and contact to ground at outer right-hand armature and back contact of relay 453. Relay 461 upon energization also locks up through its right-hand winding independently of relay 460 by way of its right-hand armature and contact. 35

Referring now to Fig. 3, it is to be observed that the energization of relay 251 completes a circuit from ground, armature and contact of relay 251, conductor 258, winding of relay 259 to grounded battery. Relay 259 is energized in this circuit and locks up through its inner right-hand armature and contact to conductor 254. 40 Similarly the energization of relay 255 completes a circuit from ground, armature and contact of relay 255, conductor 260, winding of relay 261 to battery and ground. Relay 261 is energized and locks up over its left-hand armature and contact to grounded conductor 254. As soon as either relay 259 or relay 261 is energized a circuit is completed from grounded battery, winding of relay 250, conductor 262, to ground at either the outer right-hand armature and contact 45 of relay 261 or the outer left-hand armature and contact of relay 259. Relay 250 is energized and connects the controlling leads 340 and 343 to conductors 263 and 264 respectively, thus opening the circuits through both windings of relay 461, and allowing this relay to deenergize. Relay 250 upon energization also completes a circuit from grounded battery, winding of relay 265, outer right-hand armature and contact of relay 250 to ground. Relay 265 is energized and connects the controlling leads 263 and 264 to controlling leads 266 and 267 respectively. 50

Regardless of what potential combinations 55 may be found on leads 266 and 267, the interval before the energization of relay 265 is sufficient to allow relay 461 to deenergize when relay 250 opens leads 340 and 343. The deenergization of relay 461 completes 60 a circuit from grounded battery, stepping magnet 605 of the switch 600, armature and back contact of magnet 605, armature and back contact of relay 606, brush 607 and its normal contact, outer right-hand armature 65 and contact of relay 460, left-hand armature and back contact of relay 461 to ground. Magnet 605 is energized and interrupts its own circuit to cause the advance of switch 60 into its second position. 70

It is to be observed at this point that as soon as the operator's finder switch 300 was positioned and relay 320 was energized, by means of circuits which it has not been considered necessary to describe in the present 75 application, a circuit was completed from grounded battery, right-hand winding of relay 466, left-hand winding of relay 467, switch arm 468, which is resting on its 20th contact, conductor 469, armature and contact of relay 320 to ground. Relays 466 and 467 are both energized in this circuit. Relay 466 is energized whenever the trunk selected is in the second five of a given tens group. Relay 467 is energized whenever the trunk is in the second ten of the given twenty. Since trunk number 19 in this particular group of trunks has been selected and since this is a trunk in the second five of the second ten, both relays 466 and 467 are 115 energized to control the proper registrations upon the lamp controlling relays. 120

With switch arm 603 in engagement with its second contact a circuit is completed from grounded battery, winding of relay 125 130

453, armature and contact of relay 467, conductor 470, brush 603 and its second contact, conductor 604, brush 341 and its associated contact, conductor 340, left-hand armature 5 and front contact of relay 250, conductor 263, left-hand armature and contact of relay 265, conductor 266, left-hand armature and back contact of relay 269, conductor 270, left-hand winding of marginal relay 271 to 10 ground. Relays 453 and 271 are energized in this circuit and relay 271 locks up over its right-hand winding and right-hand armature and contact to grounded conductor 254. It is to be observed that if the line 15 selected had not been in the second ten, relay 467 would not have been energized. The circuit of relay 453 would then have extended by way of a resistance 471 to conductor 470. The completion of this circuit 20 would have allowed relay 453 to be energized but in this case relay 271 would not have been energized.

The energization of relay 453 opens the locking circuit of relay 460 and this relay 25 deenergizes. At its inner right-hand armature and front contact, relay 453 completes a circuit from grounded battery, winding of magnet 605, armature and back contact 30 of such magnet, armature and back contact of relay 606, brush 607 and its second contact, inner right-hand armature and front contact of relay 453 to ground. Magnet 605 is energized and interrupts its own circuit to 35 advance the various brushes of switch 600 into engagement with their third contacts respectively.

As soon as brush 601 engages its third contact, a circuit is completed from ground, armature and front contact of relay 466, 40 conductors 472 and 473, brush 601 and its third contact, conductor 602, brush 344 and its associated contact, conductor 343, inner 45 right-hand armature and front contact of relay 250, conductor 264, right-hand armature and contact of relay 265, winding of sensitive relay 272, conductor 273, right-hand winding of marginal relay 274 to 50 grounded battery. Marginal relay 274 and relay 272 are energized in this circuit. It is to be observed that had the line selected 55 been in the first five of either the first or second ten of the trunk group, relay 466 would not have been energized. As a result the circuit extending from grounded battery, through relays 274 and 272 would have 60 been extended to ground through a resistance 474. The presence of this resistance would have prevented the energization of relay 274. Relay 272 would, however, have been energized as just described.

At its right-hand armature relay 272 completes a circuit from grounded battery, winding of relay 269, left-hand armature and back contact of relay 277, conductor 278, 65 right-hand contact and armature of relay

272 to ground. Relay 269 is energized in this circuit and prepares a locking circuit for itself through its right-hand armature and contact and through the winding of relay 277. This circuit, however, does not 70 become effective to allow relay 277 to be energized until relay 272 is deenergized. The energization of relay 269 does, however, open the circuit of relay 453 which relay 75 was maintained energized in the third position of switch 600 over its original energizing circuit. When the circuit of relay 453 is opened this relay deenergizes and completes a circuit from grounded battery, 80 winding of magnet 605, armature and contact of magnet 605, armature and contact of relay 606, brush 607 and its third contact, inner right-hand armature and back contact of relay 453 to ground. Magnet 605 is energized and interrupts its own circuit to 85 advance the brushes of switch 600 into engagement with their fourth contacts respectively.

As soon as brush 601 leaves its third contact the circuit of relays 272 and 274 is 90 opened. Relay 274 is maintained energized due to the fact that upon energization it was locked up through its left-hand winding and left-hand armature and contact to 95 grounded conductor 254. Relay 272, however, deenergizes and allows relay 277 to operate in the manner usual for counting relays. With relay 277 energized a circuit is completed from ground, left-hand armature and back contact of counting relay 279, 100 inner right-hand armature and front contact of relay 277, left-hand armature and front contact of relay 269, conductor 266, thence over a previously described circuit to battery and ground through the winding of relay 453. Relay 453 is energized and completes a circuit at its inner right-hand armature for advancing the brushes of switch 600 105 into engagement with their fifth terminals 110 respectively.

With brush 601 in engagement with its fifth terminal a previously traced circuit is completed for relays 274 and 272, the only difference being that this circuit now extends by way of the fifth contact of brush 601 instead of by way of the third contact of such brush. Relay 272 is energized and at its right-hand armature completes a circuit from grounded battery, winding of relay 279, left-hand armature and back contact of relay 280, left-hand armature and front contact of relay 277, conductor 278 to ground. Relay 279 is energized and prepares a circuit for relay 280. It is to be noted that relay 272 operates as a stepping relay to control the successive actuation of the counting relay group comprising relays 269, 277, 279, 280 and 281.

Relay 279 at its left-hand armature opens 120 the energizing circuit for relay 453 and this 125

relay deenergizes to cause stepping magnet 605 to advance the brushes of switch 600 into engagement with their sixth terminals respectively.

- 5 As soon as brush 601 leaves its fifth contact relay 272 is deenergized and allows relay 280 to become energized and lock up in series with relay 279 to grounded conductor 254. Relay 280 at its inner right-hand 70 armature and front contact completes a circuit from ground over the left-hand armature and back contact of relay 281, inner right-hand armature and front contact of relay 280, left-hand armature and front contact of relay 279 inner right-hand armature and front contact of relay 277, left-hand armature and front contact of relay 269 to conductor 266 to grounded battery through the winding of relay 453. Relay 10 75 20 453 is energized and completes a circuit for stepping magnet 605 to advance switch 600 into its seventh position. When brush 601 engages its seventh terminal relay 272 is energized to cause the energization of relay 281. Relay 281 is energized and locks up over its inner right-hand armature and front contact to grounded conductor 254 and at its left-hand armature removes the holding ground for relay 453. Relay 453 80 25 deenergizes, but does not cause switch 600 to move out of position 7 since the circuit of stepping magnet 605 is open at the right-hand armature and contact of relay 606 which was energized as soon as brush 608 85 30 engaged its seventh contact, due to the closure of a circuit from grounded battery, winding of relay 606, brush 608 and its associated contact, brush 480, which is in engagement with the twentieth terminal in the 90 35 40 arc served by it, to ground.

It is to be observed that had switch 400 seized trunk No. 15 in the third group, brush 480 would have been in engagement with its sixteenth terminal and therefore switch 600 would have been brought to rest with its brushes in engagement with their third terminals respectively. In this case relay 269 would have been the only one of the counting relays in Fig. 4 to have been 105 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 is now in the first five of a given ten and therefore relay 274 would not have been energized with the result that when relay 206 was energized, a circuit would have been completed as is obvious for lamp No. 0 in the units group.

It is thought from the foregoing description the operation of the indicator in controlling the indication of any desired number may be readily understood.

As soon as the operator observes the lighting of the lamps 0, 5 and 9 in the hundreds, tens and units groups respectively, she will insert a plug 265 into jack 267 associated with trunk No. 59. A circuit is thereupon completed from grounded battery, lamp 266, sleeve contacts of plug 265 and jack 267, winding of slow release relay 520 to ground. Relay 520 is energized in this circuit and completes a circuit for slow release relay 502. Relay 502 is energized and establishes a locking circuit for itself through its inner right-hand armature and front contact. The operation of relay 502 causes the trunk indicator to be restored to normal by means of circuits which are started into operation by a circuit completed at the outer right-hand armature and front contact of relay 502 by way of conductor 454. The ground supplied to conductor 454 operates to deenergize certain relays, not shown, but whose operation may be readily understood by reference to the above-mentioned application. The deenergization of these relays removes the holding ground from the conductor 290 which has been maintaining relays 207 and 205 energized. As soon as this ground is removed, relays 205 and 207 are deenergized, since the original ground supply which caused the energization of these relays has been removed at the left-hand armature and back contact of relay 206, due to the energization of this relay. As soon as relay 207 deenergizes the locking circuits for the various lamp controlling relays are broken and all of these relays are deenergized. The deenergization of relay 207 also opens the circuit of the relay 610 which has been energized throughout the operation of the system. This relay was energized as soon as the operator's finder switch 300 was positioned over a circuit extending from grounded battery, winding of relay 610, conductor 611, brush 391 and its associated contact, conductor 392 to grounded conductor 254. As soon as relay 610 deenergizes a circuit is completed from grounded battery, winding of stepping magnet 605, armature and back contact of magnet 605, armature and back contact of relay 606, which was deenergized as soon as switch 400 was restored to its normal position by means of circuits which it has not been considered necessary to disclose, brush 612 and its seventh contact, armature and back contact

of relay 610 to ground. Magnet 605 is energized and continues to interrupt its own circuit until the brush set has been rotated through a complete cycle and back into its normal position at which time brush 612 ⁷⁰ will fail to supply ground and the switch will be brought to rest.

All of the indicating apparatus has now been restored to its normal condition and is ready for reuse.

The manner in which the connection is completed and broken down after the completion of conversation will not be described since it is identical with that described in the previously mentioned application which ⁸⁰ completely discloses the system with which the present invention is arranged to co-operate.

What is claimed is:

1. In a number indicating system, selectively operable indicating devices, controlling means therefor, a plurality of multiposition switching devices, means to operate a desired one of said switching devices, and means to variably operate said controlling ⁸⁵ means in accordance with which one of said switching devices has been put into use and in accordance with the particular position assumed by said switching device.

2. In a number indicating system, selectively operable indicating devices, controlling means therefor, a plurality of multiposition switching devices, means to operate a desired one of said switching devices, an auxiliary switch, means to cause said auxiliary switch to assume a position determined by the position of said operated switching device, and means to variably operate said controlling means in accordance with the positions assumed by said ¹⁰⁰ switching device and by said auxiliary switch.

3. In a number indicating system, indicating devices, controlling means therefor, a plurality of lines divided into major groups, minor groups and subgroups, switching devices, means to operate one of said switching devices to seize a desired one of said lines, a plurality of controlling relays, means to energize said relays in variable combination in accordance with the major group, minor group, and subgroup in which the selected line appears, and means to variably operate said controlling means in accordance with the condition of said controlling relays.

4. In a number indicating system, groups of lines, selectively operable indicating devices, controlling means therefor, a plurality of multiposition switching devices, means to operate a desired one of said switching devices to seize a desired line, and auxiliary switch, means to cause said auxiliary switch to assume a position determined by the setting of said switching device, means operative during the first portion of the move.

- ment of said auxiliary switch to variably operate said controlling means in accordance with group designations, and means to operate said controlling means during the final 5 movement of said auxiliary switch to count off a number corresponding to the extent of travel of said switching device.
5. In a number indicating system, indicating devices, controlling means therefor 10 comprising various relay combinations and a set of counting relays, a plurality of multiposition switching devices, means to operate a desired one of said switching devices, means to variably operate said relay combinations in accordance with which one of said switching devices has been put into use, and means to operate said counting relay group in accordance with a particular position assumed by said switching device.
- 20 6. In a number indicating system, indicating devices, controlling means therefor comprising various relay combinations and a set of counting relays, a plurality of multiposition switching devices, means to operate a desired one of said switching devices, an auxiliary switch, means to set said auxiliary switch in a position determined by the position assumed by said switching device, means to variably operate said relay combinations in accordance with which one of said switching devices has been put into use and in accordance with the position assumed by said switching device, and means to operate said counting relay group in response to the advance of said auxiliary 35 switch into a position determined by the position of said switching device.
7. In a number indicating system, indicating devices, controlling means therefor, a 40 plurality of multi-position switching de-

vices each provided with a plurality of brushes, a contact bank individual to each of said switching devices and arranged for engagement by said brushes, a plurality of lines terminating in said contact banks, 45 means to render a given line busy upon seizure by the brush set of a switching device, means to cause a desired one of said switching devices to hunt for an idle line, and circuits completed through certain ones 50 of said brushes in the set position of said switching device for operating said controlling means to cause said indicating devices to register a number corresponding to the idle line seized by said switching device.

8. In a number indicating system, indicating devices, controlling means therefor, a plurality of multi-position switching devices each provided with a plurality of brushes, a contact bank individual to each of said switching devices and arranged for engagement by said brushes, means to cause a desired switching device to select an idle contact set, means to thereupon render said contact set non-selectable by other switching devices, an auxiliary switch, and circuits completed through certain ones of said brushes in the set position of said switching device and dependent on the position assumed by said auxiliary switch for operating said controlling means to cause said indicating devices to register a number corresponding to the number of the idle contact set selected.

In witness whereof, I hereunto subscribe my name this 19th day of December, A. D. 1919.

EDGAR H. CLARK.
